UNITED STATES PATENT OFFICE.

FREDERIC SCHAEFER, OF PITTSBURGH, PENNSYLVANIA.

REINFORCED CONNECTING BAR.

Application filed December 10, 1921. Serial No. 521,346.

To all whom it may concern:

Be it known that I, FREDERIC SCHAEFER, a citizen of the United States, and a resident of Pittsburgh, in the county of Allegheny 5 and State of Pennsylvania, have invented a new and useful Improvement in Reinforced Connecting Bars, of which the following is a specification.

This invention relates to connecting bars 10 for use with the brake levers of railway car trucks, or for use as push rods for brake cylinders, and other similar constructions. More particularly it relates to such bars formed from rolled and pressed metal. 15 Connecting bars of this general type are already well known in the art, and are illustrated and described in detail in my prior patents Numbers 1240493, 1211763, 1263608, 1309220 and others. Such bars are formed 20 from sheet metal, slotted at the ends and bent to hollow form with the slotted end portions forming parallel ears provided with holes for engaging connecting pins, as is understood in the art.

25 The particular object of the present invention is to provide such a bar so formed that a minimum of metal will be required for constructing it, and so that it will be longitudinally reinforced at the certain 30 points, and so that the reinforcing portions may be formed by the original rolling operation.

Referring to the drawings, Fig. 1 shows a rolled blank or sheet from which one of 35 the bars embodying this invention is to be formed; Fig. 2 shows the same blank after its ends have been shaped and slotted; Fig. 3 shows the blank after the slotted ends have 40 been subjected to a forging operation; Fig. 4 is an end view of the blank shown on Fig. 3, with its final form indicated in dotted lines; Fig. 5 shows the bar in final shape as 45 formed by bending the blank of Fig. 3 upon itself to bring the edges into contact; Fig. 6 is a side view of the completed bar; Fig. 7 is an end view thereof, and Figs. 8, 9, 10 and 11 are sections taken upon the lines 8—8, 9—9, 10—10 and 11—11 of Fig. 6.

The improved connecting bar is formed by 50 rolling the metal sheet or blank 1 with flanges 2 at the edges thereof. These blanks may be rolled in sheets of any desired length, and cut up to suitable lengths, as will be observed. On the back of the sheet 1, along 55 its middle portion may be formed a raised, rounded reinforcing portion 3. This por-

tion is not essential, but is preferred. After the blanks have been cut to suitable length, as shown in Fig. 1, the ends are slotted at the middle, and each portion of the slotted 60 ends is rounded off, as shown in Fig. 2. In this slotting the metal is displaced laterally, none of it being cut out from the blank. Then these slotted ends are subjected to a forging operation which forms the longitudinal raised portions, or embossments 5. 65 The same operation turns in the inner edges of the ends along the slot 4, forming interior flanges 6, extending around the ends on each side of the slots 4. At the same time 70 the metal around the pin holes 7 is formed into raised flanges, or embossments 8, for the purpose of increasing the bearing through which the connecting pins extend, as is well understood in the art. In forming 75 the embossments 8 a certain amount of metal is drawn from the flanges 2 and 6, so that the intermediate portion 10 of the sheet is not materially thinned out by the formation of these raised portions about the pin 80 eyes. The metal required for the flanges 8 is supplied chiefly from the excess provided by the thickened portions 2 and 3 of the original blank.

After this formation of the end portions 85 has been completed by the forging operation above referred to, the blank as shown in Fig. 3 is rolled upon itself about a circular or elliptical former until the corners of the edge flanges 2 come into contact along the 90 length of the body portion of the bar. It will be understood that at each end this contact of the edges terminates a little short of the base of the slots 4, so that the ear members 11 may lie in parallel planes, as 95 illustrated in Figs. 5 and 7, and as is usual in the art.

As shown in Figs. 8 and 9, the body portion of the bar is reinforced at its top and bottom by means of the extra metal contained in the thickened portion 3, and also by the meeting flanges 2 at the opposite side of the bar. The intermediate portion of the body may be made of comparatively thin sheet metal and on account of its circular 100 shape, and reinforced edges and back, will give maximum strength in proportion to the weight of metal used.

By constructing these connecting bars in this form, I am enabled to use a thin metal 110 blank, securing the necessary rigidity by means of the additional metal contained in

the flanges 2, and the rib 3 intermediate the edges. In addition, in the formation of the ears 13 the extra metal in the flanges 2 is available for use in forming the flanges 8 about the pin eyes. Furthermore, the flanges on the edges of the plate used for making this bar coming into contact as shown in Figs. 8 and 9 not only give the appearance of a thicker metal and reinforce the edges thereof, but by the closure of the edges of the sheet as illustrated form a hollow bar of substantially greater radius than would be possible without the use of the flange. That is to say, the diameter of the bar is substantially increased by having these flanges at the edge of the sheet, and this gives additional strength to the bar because of the increased radius, as well as because of the increase of metal in the flanges themselves.

20 The connecting bar described is of comparatively light weight, and of maximum strength for its weight. The bar can be produced by simple and practical manufacturing operations, the longitudinal flanges 25 being rolled on the original blank, and the additional flanges and embossments being formed by one forging operation after the blank is slotted at its ends. Or the slotting and forming of the finished ears may be performed at one forging operation. The extra metal in the flanges and rib is utilized to form the bases about the pin eyes. The bar is reinforced at all places where weakness would otherwise exist, so as to resist all 35 stresses to which such bars are subjected. It meets the exacting requirements for bars of this character and will withstand the severe conditions encountered in railway service.

I claim:

- 40 1. A connecting bar comprising a one piece hollow body member formed from a sheet of metal having raised flanges along each edge, the sheet being bent upon itself to bring said flanges into contact.
- 45 2. A hollow connecting bar formed from a metal sheet having its edges turned up to form reinforcing flanges, and having a reinforcing rib extending longitudinally along the bar intermediate the flanges.
- 50 3. A connecting bar comprising a metal blank bent upon its self to form a hollow

body member, said blank having a longitudinal thickened portion, the ends of the bar being formed into perforated ear members, the metal in said ear members being forged 55 to form raised flanges surrounding the perforations therein.

4. A connecting bar comprising a one piece hollow body member slotted at its ends to form oppositely disposed ears, said body 60 member being formed from a piece of sheet metal having thickened reinforcing edges, and an intermediate longitudinal reinforcing portion disposed along the body of the bar between the edges. 65

5. A connecting bar comprising a hollow body member turned up from a blank, said blank comprising a sheet having longitudinal thickened edges and an intermediate longitudinal rib, the ends of said bar being 70 formed into perforated ear members, the metal of the ear members being forged to form raised bounding flanges surrounding the perforations therein. 75

6. A connecting bar comprising a body 75 member formed from a ribbed blank and having forged terminal perforated ear members, flanges surrounding the perforations of the ear members, said flanges being formed in part from the excess metal supplied by 80 the said ribs of the blank.

7. A connecting bar comprising a hollow body member formed from a sheet of metal having raised flanges along each edge and a longitudinal reinforcing rib, said bar having 85 its ends forged into perforated ear portions, the perforations being surrounded by raised flanges forged from the metal of the said edge flanges and reinforcing rib. 90

8. A connecting bar comprising a one-piece hollow body member having a longitudinal slot throughout, the meeting edges being thicker than the adjacent body portion, a longitudinal reinforcing rib intermediate the edges, and forged terminal ear members 95 having reinforcing flanges surrounding pin eyes formed in the ear members. 95

In testimony whereof, I sign my name.

FREDERIC SCHAEFER.
